UNITED STATES PATENT OFFICE.

OSKAR GUNTHER, OF KELLOGG, IDAHO.

MAIL-BAG DELIVERING AND RECEIVING APPARATUS.

No. 914,039.

Specification of Letters Patent.

Patented March 2, 1909.

Application filed October 8, 1908. Serial No. 456,748.

To all whom it may concern:

Be it known that I, OSKAR GUNTHER, a citizen of the United States, residing at Kellogg, in the county of Shoshone and State of Idaho, have invented certain new and useful Improvements in Mail-Bag Delivering and Receiving Apparatus, of which the following is a specification, reference being had therein to the accompanying drawing.

10 This invention relates to improvements in mail-bag delivering and receiving apparatus.

The object of this invention is the production of means for facilitating the delivery of mail-bags to and from a moving car.

15 Another object of this invention is the production of a mail bag receiving apparatus, which will after the bag has been delivered thereon, be thrown out of the way of passing trains.

20 Still another object of this invention is the production of a mail-bag delivering and receiving apparatus which is simple in construction, efficient in operation and consists of a comparatively small number of parts.

25 With these and other objects in view, this invention consists of certain novel constructions, combinations, and arrangements of parts, as will be hereinafter fully described and claimed.

30 In the drawings: Figure 1 is a perspective view, showing my improved apparatus in connection with a car. Fig. 2 is a plan view of the mail-receiving apparatus. Fig. 3 is a detail sectional view of the locking device, 35 for holding the receiving apparatus in an operative position. Fig. 4 is a detail of one of the ends, of the mail-bag supporting means. Fig. 5 is a detail of the connecting means, connecting the upper outwardly extending 40 arm and the vertical rod of the mail-bag supporting means carried by the car. Fig. 6 is a detail sectional view of the joint of the lower sectional supporting arm.

Referring to the drawings by numerals, 1 45 designates a mail-bag receiving fork, which is carried by the car, and journaled at each end in a bracket 2. The fork 1 is adapted to receive a mail-bag, supported to one side of the car. Angle brackets 3 and 4 are secured 50 to the out side of the car upon each side of the door. Apertures 5 are formed in brackets 3 and 4, for the receipt of the vertical rod 6 of the mail-bag supporting device. A hook 12^a is so positioned upon the bracket 4 so as to 55 limit the movement of the mail-bag supporting device in one direction. The vertical rod

6 is provided with a square portion 7, upon which fits a sleeve or cylindrical number 8 and a thumb screw 9 passes through said sleeve 8 and firmly secures said sleeve to said 60 vertical rod 6. The sleeve or cylindrical portion is formed upon the inner end of the upper outwardly extending arm 10. The lower arm 11 is fixedly secured at its inner end 12 to the vertical rod 6. 65

Upon the outer end of each of the outwardly extending arms 10 and 11 is positioned a catch device 13 for engaging rings upon each end of a mail bag. This catch device consists of a pivoted member 13', which is 70 pivotally mounted in the bifurcated ends 14 of said rods or arms. A flat spring 15 is fixedly secured at its inner end to the outer end of said rod or arm and said spring is bowed inwardly near its outer end and engages the 75 outer end of the pivoted member 13'. When the bag is caught, to be removed from the catch device 13 the pivoted member 13' will swing upon its pivot and the bag can be removed or withdrawn from the swinging 80 member 13' which will swing to the position shown in dotted lines in Fig. 4 and indicated by 13^a, thereby allowing the bag to be easily removed from said member 13'. 85

Positioned to one side of the track is a standard 16, which is provided with an upper bifurcated end 17, in which is pivotally mounted an arm 18, which carries at one end a weight 19 and at its opposite end a catch-device 13. The purpose of the weight is to 90 raise the arm 18, in a vertical position out of the way of passing trains. Below the arm 18 is positioned a sectional arm 20, which is secured at its inner end to the standard 16. The upper section 21 of the arm 20 is hinged 95 to the outer end of the section 22 at 23, and as soon as the mail-bag is removed off the catch device 13 carried by the arms 18 and 20, section 21 will drop down out of the way of passing trains. The section 21 is provided 100 with an inner bifurcated end 21^a, in which fits the reduced extension 22^a formed upon the outer end of the section 22 of the lower arm 20, thereby forming a hinge connecting said sections together. The reduced extension 22^a is provided with a cut-out portion 22^c and a pin 22^d is positioned through the bifurcated end and through said cut-out portion in said reduced extension 22^a so as to 105 limit the upward movement of the section 21 110 of the arm 20.

The mail receiving device 24 is secured to

the section 22 of the arm 20 by means of the cylindrical portion or sleeve 25 of the member 26, of the receiving device, passing over or around said section 22. Upon one side of the cylindrical portion 25 are positioned two 5 perforated lugs 26 and between the same is pivoted the locking member or trigger 27 by means of the pin 28 passing through the perforation in said lugs, 26. The locking member 27 is provided at its inner end with a 10 downwardly extending portion, which passes through the aperture 29 in the cylindrical portion 25. Notches 30 are formed upon the section 22 of the arm 20 and said downwardly 15 extending portion of the member or trigger 27 engages in said notches and holds the receiving device 24 in a position, so as to receive a mail-bag supported by the mail-bag supporting device carried by the car.

20 The jaw 31 is pivotally mounted upon the jaw 26 at 32 and said arm is provided at its inner end with a pin 33, which pin extends for considerable distance upon each side of the jaw or arm 31. Connected near the end 25 33 is a cable 34, which is provided at one end with a head 35, which is positioned in a cylinder 36, which cylinder is supported from the sides of the section 22 of the arm 20 by means of brackets 37. A spring 38 is positioned around the cable 34 having one end resting against the hook 35 and the other resting against the end 39 of the cylinder 36.

A chain 40 is secured to the outer end of the jaw 31 at 41 and to the inner end of the 35 trigger 42 at 43. The trigger 42 is provided with a forked end 44, which straddles the jaw 31 near its outer end. The jaw or rod 26 is provided with a notch 45 and the end 46 of the trigger 42 is adapted to engage in said notch. 40 By this means the outer ends of the members or jaws 26 and 31 are held apart, but as soon as the trigger 42 is struck by the bag, said trigger will be knocked out of the notch 45 of the jaw 26 and by means of the spring 38 positioned around the cable 34 in the cylinder 36, the jaw 31 will immediately close and thereby hold the mail-bag between the jaws. 45 When the jaw 31 is swung in a closed position, the pin 33 which extends both above and below the jaw 31 will engage the member or latch device 27 and withdraw the downwardly extending end from the notch 30 and the receiving device 24 will be allowed to swing downwardly out of the way of moving 50 trains.

When it is desired to receive mail from trains passing in the opposite direction from that shown in the drawing, the arm or jaw 31 may be placed upon the opposite side of the jaw 26 and the whole device rotated and the same held in the position to receive the mail-bag by means of the lever or member 27 engaging one of the notches 30 upon the opposite side of the section 22 of the arm 20. 60

65 The mail-bag supporting means carried by

the car may be placed upon the opposite side of the door from that shown in the drawing, in case the car is desired to be moved in the opposite direction.

What I claim is:

1. In an apparatus of the character described, the combination with a support, of brackets secured to said support, said brackets provided with apertures, mail-bag supporting means pivotally mounted within 75 said apertures, said mail-bag supporting means comprising a vertical rod, an upper and lower arm extending therefrom, means positioned upon the ends of said arms for retaining a mail-bag, and a hook-shaped member secured to said bracket and straddling the lower arm and limiting the rotary movement of said mail bag supporting means in one direction.

2. In an apparatus of the character described, the combination with a mail-bag supporting means, of a vertical rod, an outwardly extending arm, a square portion formed upon said vertical rod near one end, a sleeve formed upon one end of said arm, 90 said sleeve provided with means for registering with said square portion upon said vertical rod, and a thumbscrew passing through said sleeve and engaging said square portion for the purpose specified.

3. In an apparatus of the character described, the combination with a support, said support provided with a bifurcated end, of an arm pivotally mounted in said bifurcated end, means formed upon one end of 100 said arm for engaging a mail-bag, and means formed upon the opposite end of said arm for raising said first mentioned end of said arm, of a sectional arm, said arm comprising an outer section, said outer section provided at its inner end with a bifurcated end, said inner section provided at its outer end with a reduced extension, said extension pivotally mounted within said bifurcated end, and a cut-out portion formed upon one side 110 of said reduced extension, a pin passing through said bifurcated end and through said cut-out portion and means connected to the outer end of said outer section and to said first mentioned arm for holding said outer section in connection with said inner section.

4. In an apparatus of the character described, the combination, of a mail-bag supporting arm provided with a mail-bag catching means rotatably mounted thereon, means connected to said mail-bag catching means for normally holding said catching means in a set position, so as to receive a bag delivered from a moving car.

5. In an apparatus of the character described, the combination with a supporting arm, of a mail bag receiving device rotatably mounted thereon, notches formed upon said supporting arm, and a latch pivotally con- 130

- nected to said receiving device and engaging with said notches upon said supporting arm for holding said receiving device in an operative position.
- 5 6. In an apparatus of the character described, the combination with a supporting arm provided with notches formed therein, of mail-bag receiving means rotatably mounted thereon, said receiving means comprising a sleeve provided with an aperture in one side thereof, ears formed upon one side of said sleeve, a latch pivotally mounted between said ears and passing through said aperture and engaging the notches formed upon said 15 supporting arm.
7. In an apparatus of the character described, the combination with a mail-bag receiving means, a stationary jaw and a movable jaw, means connected to one end of said 20 movable jaw and exerting an inward pull thereon, a trigger secured upon one end to the outer end of said stationary jaw and straddling at its other end the stationary jaw and means adapted to spring the trigger 25 and close said jaws.
8. In an apparatus of the character described the combination with a mail-bag receiving means comprising a stationary jaw, and a movable jaw pivotally mounted there- 30 on, of a trigger positioned between the ends of said jaw, and adapted to hold said ends apart, said trigger provided with a forked end, said forked end straddling the outer end of said pivoted jaw, and a chain attached to 35 said outer end and said forked end of said trigger, and means secured to the opposite end of said pivoted jaw and exerting an inward pull for closing said jaws when said trigger is detached therefrom.
- 40 9. In an apparatus of the character described, the combination with a supporting arm, of a mail bag receiving means mounted thereon, said means provided with a stationary jaw, brackets secured to said sup- 45 porting arm, said brackets supporting at one end a casing, a cable secured to one end of said pivoted jaw, a plunger positioned within said casing, and means positioned around said cable in said casing for exerting an in- 50 ward pressure upon said plunger.
10. In an apparatus of the character de- scribed the combination with a supporting arm, of a mail-bag supporting means mounted upon said supporting arm and adapted to be rotated upon said supporting 55 arm, said means comprising a plurality of jaws, one jaw pivotally mounted upon the other jaw, means positioned between the outer ends of said jaws for normally holding said ends apart, means connected to the opposite end of said pivoted jaw for exerting an inward pull, means passing through said jaw near said end and coöperating with means positioned upon said other, for allowing said catching means to rotate. 60
11. In an apparatus of the character described, the combination with a supporting arm, of a mail-bag supporting means mounted thereon, said means comprising a sleeve and a stationary jaw, said sleeve 70 formed upon one end of said stationary jaw, means positioned upon said sleeve and passing through said sleeve for holding the catching means in an operative position, and a pivoted jaw secured to said stationary jaw 75 and provided with means upon its inner end for engaging said means upon said stationary arm for rotating said receiving means.
12. In an apparatus of the character described the combination with a supporting 80 arm, of a receiving device, mounted thereon, said receiving device comprising a stationary arm provided with a sleeve formed upon one end thereof and straddling said supporting arm, a latch device, secured to said sleeve 85 and passing through the same, notches formed upon said stationary jaw, said pivoted jaw mounted upon said stationary jaw, said pivoted jaw provided at its inner end with a pin, said pin adapted to engage said 90 trigger or latch and withdraw the same from said notches and allow said receiving means to rotate, and means connected to said end of said pivoted member for exerting inward pressure upon said pivoted jaw. 95
- In testimony whereof I hereunto affix my signature in presence of two witnesses.
- OSKAR GUNTHER.
